US00D737771S

(12) **United States Design Patent**
Hofmann

(10) **Patent No.:** **US D737,771 S**
(45) **Date of Patent:** **** Sep. 1, 2015**

(54) **ELECTRICAL CONNECTOR**

(71) Applicant: **NEUTRIK AG**, Schaan (LI)

(72) Inventor: **Thomas Hofmann**, Buchs (CH)

(73) Assignee: **NEUTRIK AG**, Schaan (LI)

(**) Term: **14 Years**

(21) Appl. No.: **29/481,211**

(22) Filed: **Feb. 3, 2014**

(30) **Foreign Application Priority Data**

Dec. 12, 2013 (EP) 001393623-0001

(57) **CLAIM**

The ornamental design for an electrical connector, as shown and described.

DESCRIPTION

FIG. 1 is a perspective view of an electrical connector showing my design;

FIG. 2 is a right side elevation view thereof;

FIG. 3 is left side elevation view thereof;

FIG. 4 is top plan view thereof;

FIG. 5 is a bottom plan view thereof;

FIG. 6 is a rear elevation view thereof; and,

FIG. 7 is a front elevation view thereof.

The broken line portion of the figure drawings is included to show unclaimed subject matter only and forms no part of the claimed design.

1 Claim, 7 Drawing Sheets
